UNITED STATES PATENT OFFICE.

JAMES G. BLUNT, OF SCHENECTADY, NEW YORK.

LATERAL-MOTION APPLIANCE FOR LOCOMOTIVE DRIVING BOXES.

Application filed September 25, 1924. Serial No. 739,794.

To all whom it may concern:

Be it known that I, JAMES G. BLUNT, a citizen of the United States, and a resident of Schenectady, in the county of Schenectady and State of New York, have invented a certain new and useful Improvement in Lateral-Motion Appliances for Locomotive Driving Boxes, of which improvement the following is a specification.

10 My invention relates to means for affording and controlling lateral motion in the driving boxes of locomotive engines, and its object is to effect a simplification of structure, and reduction of weight, as well as to permit the location of the driving springs on the inside of the frame of the locomotive.

The improvement claimed is hereinafter fully set forth.

20 In the accompanying drawings: Figure 1 is a vertical transverse section, through a driving axle of a locomotive engine, illustrating an embodiment of my invention, the inner side of the frame member being shown 25 in elevation; Fig. 2, a transverse section, through the frame members, the left hand half being shown as taken in the vertical axial plane of a driving axle, and the right hand half in a vertical plane exterior to the 30 axle; Fig. 3, an isometrical view of one half of the driving box; and, Figs. 4 and 5, similar views of a spring seat, as seen from its top and its bottom, respectively.

In the practice of my invention, referring 35 descriptively to the specific embodiment thereof which is herein exemplified, the driving box, 4, is, in and of itself, substantially similar to those in existing practice, and is similarly adapted to the regular conditions thereof. On account of machine 40 limitations, it is usually made, as shown, in two half sections, bolted together in the middle longitudinal plane of the locomotive, and extends continuously, between the hubs 45 of the driving wheels 6, at its ends. This driving box is mounted, in the usual manner, in pedestals, 3, of the side frame members, which comprise the top rails, 1, and bottom rails, 2, of frames of the bar type. Crown 50 bearing, 4^c, in which the journals, 8, of the driving axle rotate, are fitted in the end portions of the driving box.

The portion of the weight of the locomotive which is supported on the driving axle, 55 is transmitted from the frame to the driving box, through springs, 5, which are located

on the inner sides of the frame members, instead of on the tops thereof, as in ordinary practice. The outer ends of the springs are connected to the upper ends of single spring 60 hangers, 9, of the sword type, the lower ends of which may be coupled, either to equilizers, 9^a, as shown, or coupled directly to the frame.

The transmission of weight from the 65 springs is effected through the following construction and relative disposition of intermediate members. Each of the spring bands, 5^a, rests in a spring seat, 7, having on the inner and outer ends of its bottom, 70 transversely extending semi-cylindrical journals, 7^a which abut on the top of the driving box, and fit against correspondingly curved shoulders on an upward bearing projection, 4^a, on the top of the driving box. 75 Lever arms, 7^b, are formed on the sides of the spring seats, said arms extending downwardly and outwardly, and bearing, at their ends on the pedestals of the frame members, as most clearly indicated at the right hand 80 side of Fig. 2. The extent of lateral traverse of the driving box, in each direction from normal middle position, is determined by the spaces, x , provided between the inner faces of the outside flanges of the driving box, and the outside of the pedestal 85 wedges, as shown in Fig. 2.

It will be seen that, in the construction above described, it becomes unnecessary to provide flanges on the driving box, for bearing on the frame members, their elimination effecting a structural simplification and a saving in weight. It will also be noted that the inside flanges of the pedestal shoes and wedges need not be as deep as the outer ones, 90 resulting in additional saving in weight, and permitting a short overall length of the spring seat. A further simplification is effected in this construction, in its adaptability to the application of single spring 95 hangers, of the sword type, instead of double hangers with forged end links and pin connections.

In the operation of a lateral motion appliance, in accordance with my invention, 100 when in normal middle position on tangent track, the springs transmit their load to the driving box and axle, through both the journals of their seats, the outer and the inner one of each seat bearing on the driving 105 box. When the driving wheels are displaced laterally, as when traversing a curve of the

2

track, the driving box is forced to move laterally with the wheels, so that the spring seat opposite the origin of the wheel displacement, will tip or tilt on the axis of its 5 inner journal, and thereby exert an upward action against the resistance of the load carried by the adjacent spring. The lever arms of the spring seat being in contact with the inner side of the adjacent frame 10 member, tends to rotate on its outer journal, lifting the inner journal from its seat, but the upward pressure thus induced, is resisted by the spring, and it therefore follows that the relative proportion of the distance 15 from the axis of the outer journal to the centre of the spring, and the distance from the axis of the outer journal, to the point of contact of the lever arms 7° , of the spring seat, with the frame member, is the proportion 20 of the load on the spring which is caused to act as resistance to lateral displacement, or, in other words, the amount of the load on this spring, which acts to return the structure to normal position, after 25 it has been displaced, therefrom.

I claim as my invention and desire to secure by Letters Patent:

1. In a locomotive engine, the combination of side frame members; a driving box, 30 fitted therein, with the capacity of relative transverse movement; springs, located on the inner sides of the frame members, and bearing thereon; spring seats, journalled on the driving box and supporting said 35 springs; and lever arms, fixed to the spring

seats and bearing on the frame members.

2. In a locomotive engine, the combination of a side frame member; a driving box fitted therein; with the capacity of relative transverse movement; a spring located on 40 the inner side of the frame member, and bearing thereon; a spring seat, journalled, at its opposite ends, in the driving box, transversely thereto, and supporting said spring; and lever arms, depending laterally 45 from the spring seat and bearing on the frame member.

3. In a locomotive engine, the combination of a side frame member; a driving box, fitted therein, with the capacity of relative 50 transverse movement; a bearing projection on the top of the driving box, having transversely extending curved bearings on its ends; a spring, located on the inner side of the frame member and bearing thereon; a spring seat, supporting said spring and having end journals fitting on the bearings 55 of the driving box; and lever arms, depending laterally from the spring seat and bearing on the frame member.

4. In a locomotive engine, a spring seat, adapted to support a spring on its top, and having transverse journals on the lower ends of its bottom, and lever arms, depending from its sides.

JAMES G. BLUNT.
